R. T. REINSPERG

EGG TRAY FOR INCUBATORS

Filed Oct. 30, 1922

Inventor

Rudolph T. Reinsberg

By

Albert J. Fisher

Attorney

UNITED STATES PATENT OFFICE.

RUDOLPH T. REINSPERG, OF LOUISVILLE, KENTUCKY.

EGG TRAY FOR INCUBATORS.

Application filed October 30, 1922. Serial No. 597,710.

To all whom it may concern:

Be it known that I, RUDOLPH T. REINSPERG, a citizen of the United States, residing at Louisville, in the county of Jefferson 5 and State of Kentucky, have invented certain new and useful Improvements in Egg Trays for Incubators; and I do hereby declare the following to be a full, clear, and exact description of the invention, such as 10 will enable others skilled in the art to which it appertains to make and use the same.

This invention relates to improvements in incubators and had for one of its principal objects the provision of an egg-holding 15 tray for an incubator which shall be so constructed and mounted in the incubator that it may be readily withdrawn from the warming cabinet, turned upside-down and as readily replaced within a very short space of 20 time, and with a minimum expenditure of time and trouble.

One of the important objects of this incubator is the provision of an improved construction whereby a tray-full of eggs, numbering approximately one hundred, or more 25 or less as the occasion requires, may be conveniently and readily turned completely over and replaced into position in the incubator without any possibility of breakage and in 30 the shortest possible space of time.

As is well known, in the hatching of eggs by artificial means, as by incubators or the like, it is necessary that the eggs be turned or shifted at regular intervals, and also that 35 they be maintained at a very even temperature throughout the hatching period. Ordinarily, this turning of the eggs requires considerable time and often allows the batch to cool, with the result that the hatching operation is not as successful as it should be.

It is the object of this invention to eliminate the above named difficulties in a practical manner.

Other and further important objects of 45 this invention will be apparent from the disclosures in the accompanying drawings and following specification.

The invention, in a preferred form, is illustrated in the drawings and hereinafter 50 more fully described.

In the drawings:

Figure 1 is a top plan view of the improved device of this invention, shown in operative position, parts being broken away.

55 Figure 2 is a side view of the device, portions being shown in section.

Figure 3 is a detail sectional view of the main operating part of the structure, taken on the line 3—3 of Figure 1, looking in the direction indicated by the arrows. 60

Figure 4 illustrates a preferred form of latching means for maintaining the two hinged halves of the tray in locked relation. As shown in the drawings:

The reference numeral 10 indicates a cabinet such as is usual in incubators, and which is designed to form a zone which may be readily heated to the required temperature. The lower portion of the cabinet, shown in the drawings, accommodates the egg tray, 70 designated broadly by the reference numeral 12, and the upper or remaining portions may be used as a brooder for the hatched chicks.

The size of the cabinet may be varied to receive any number or sizes of trays, and 75 any convenient heating means may be used. The heating means forms no part of the present invention and is not illustrated.

The cabinet 10 is fitted up with suitable grooves or slides 14 adapted to slidably 80 receive tray supports in the form of bars 16, which may be of any desired material, as wood or metal. These bars 16 are of substantially the same length as the grooves 14, and are adapted to be pushed back to 85 their fullest extent into said grooves when the cabinet is closed. A pair of said bars or supports is provided for each tray 12.

Each of the supports or bars 16 is provided with a longitudinally extending slot 90 or runway 18. The slot or runway 18 is enlarged in the middle of the bar 16 forming longitudinally extending depressions along both the upper and lower surfaces thereof for the accommodation of a roller or the like 20. The rollers are mounted on axles 22 fitted into opposite sides of the tray 12 and at approximately the middle portion of each side. In this manner it will be evident that the tray may be readily turned on an 100 axis formed by the axles 22 and rollers 20, especially when the rollers are supported in the grooves 18 provided therefor.

The grooves 18 are provided with extensions 24 at right angles thereto and extending upwardly therefrom at their outer ends, as best shown by the dotted lines in Figure 2. These extensions provide for the ready removal of the trays from the cabinet when such removal is desired or necessary, and 110 the slots 18 permit of longitudinal motion of the tray 12 with respect to the bars 16,

while the tray is either in or out of the cabinet 10.

As shown, the rectangular tray is made in two sections, 26 and 28, adapted to fit together closely and each part of the tray is provided with a cover of wire or similar material, so that the heated air of the incubator may readily gain admittance to the eggs. Partitions or spacing members 30 are positioned in the tray members 26 and 28 so that the eggs may be properly spaced from each other, and to moreover retain them in position whenever the tray is turned in accordance with the principles of the invention.

It will be noted that the partitions 30 of the top portion of the tray 28 are deeper than the corresponding partition members 32 of the lower tray 26. This is to provide a means of free egress for the chicks when hatched, as the upper tray 28 is removed a few hours before the eggs are due to hatch out, thereby allowing the chicks to scramble over any remaining eggs and the low partitions 32 to an opening 34 provided in the tray through which they can drop to the brooder below. The opening 34 is normally closed, except at the time when the eggs are opening.

A spring impelled pin 36 is mounted in a suitable socket in each of the bars 16, and the free ends of the pins are adapted to engage in depressions 38 in the tray members 26, by which means accidental displacement of the tray is prevented.

The trays 26 and 28 are locked into operative relation with each other by means of hooks 40 at the back of the tray, and a latch 42, or similar element at the front thereof.

The operation is as follows:

The tray 12 is withdrawn from the cabinet in an obvious manner and the lower portion filled with eggs, after which the upper mem-

ber is locked into position thereon. The incubation is then started, after the tray has been pushed into position in the cabinet. At regular intervals, the tray is withdrawn through the opening in the cabinet, which is ordinarily closed by the door 44. The application of a slight force will serve to disengage the pins 36, after which the tray can be completely turned over on the axis formed by the axles 22 and which operate by means of the rollers 20. The pins 36 automatically lock the tray in its new position, and it can be immediately replaced in the cabinet.

It will be seen that by means of this improved invention, an entire lot of eggs in process of incubation can be readily and conveniently turned in a minimum period of time, thereby eliminating any danger of undue cooling, and saving the labor of turning the eggs singly by hand or otherwise.

I am aware that many changes may be made, and numerous details of construction varied through a wide range without departing from the principles of this invention, and I therefore do not purpose limiting the patent granted hereon otherwise than as necessitated by the prior art.

I claim as my invention:

An incubator including a cabinet, a door in said cabinet, supporting bars slidably through the opening covered by the door, and a two-section egg tray slidably and removably mounted in said supporting bars, said egg-tray comprising a pair of interfitting wire-bottom sections, and egg-spacing and retaining partitions rigidly fastened to each section, the partitions in one section being of greater height than those of the other section.

In testimony whereof I affix my signature.

RUDOLPH T. REINSPERG.
